DESIGN FOR A NEWSPAPER BOY STATUETTE

Clayton J. Beaver, Long Beach, Calif.

Application September 6, 1944, Serial No. 115,199

Term of patent 14 years

(Cl. D29—23)

To all whom it may concern:

Be it known that I, Clayton J. Beaver, a citizen of the United States and a resident of Long Beach, county of Los Angeles, State of California, have invented a new, original, and ornamental Design for a Newspaper Boy Statuette, of which the following is a specification, reference being had to the accompanying drawing, forming part thereof.

I claim:

The ornamental design for a newspaper boy statuette, substantially as shown.

CLAYTON J. BEAVER.
